UNITED STATES PATENT OFFICE.

HAROLD W. HODGETTS, OF SPRINGFIELD, MASSACHUSETTS, ASSIGNOR TO THE STRONG MANUFACTURING COMPANY, OF WINSTED, CONNECTICUT, A CORPORATION OF CONNECTICUT.

DESIGN FOR A COFFIN-HANDLE.

43,960.

Specification for Design.

Patented May 6, 1913.

Application filed December 21, 1912. Serial No. 738,074. Term of patent 7 years.

To all whom it may concern:

Be it known that I, HAROLD W. HODGETTS, a citizen of the United States, residing at Springfield, county of Hampden, and State of Massachusetts, have invented a new, original, and ornamental Design for Coffin-Handles, of which the following is a specification, reference being had to the accompanying drawing, forming part thereof, and

which is a view of a coffin-handle showing my new design.

I claim:

The ornamental design for a coffin handle as shown.

HAROLD W. HODGETTS.
